UNITED STATES PATENT OFFICE.

THOMAS M. RENICK, OF MORGANTOWN, WEST VIRGINIA.

WRENCH.

Application filed December 31, 1921. Serial No. 526,211.

To all whom it may concern:

Be it known that I, THOMAS M. RENICK, a citizen of the United States, residing at Morgantown, in the county of Monongalia and 5 State of West Virginia, have invented a new and useful Wrench, of which the following is a specification.

This invention relates to tools, and more particularly to wrenches, the primary object 10 of the invention being to provide a quick-acting wrench, and one which may be operated in places where space is limited.

Another object of the invention is to provide a wrench wherein the operating handle 15 may be adjusted with respect to the body portion thereof, to facilitate the use of the wrench.

A still further object of the invention is the provision of a removable head constructed to receive a plurality of jaws of various 20 sizes.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 25 within the scope of what is claimed, without departing from the spirit of the invention.

Referring to the drawing:

Figure 1 is a side elevational view of a wrench constructed in accordance with the 30 present invention, parts thereof being broken away to illustrate the operating means.

Figure 2 is an elevational view of the jaw supporting head.

40 Figure 3 is a front elevational view of a wrench.

Figure 4 is a view of the removable jaw and

45 Figure 5 is a sectional view through the head disclosing a jaw as positioned therein.

Referring to the drawing in detail, the body portion of the wrench is indicated at 5 and includes a tubular portion formed with an enlargement 6 at one end thereof, the enlargement having its outer surface threaded 50 throughout a portion of its length, as at 7.

The opposite end of the body portion 5 is internally threaded as at 8 to accommodate the threaded bearing member 9 in which the 55 operating shaft 10 moves. Disposed within

the body portion is a securing collar 11 which is mounted on the operating shaft 10, and is formed with an opening to accommodate the screw 12 which has its threaded portion embedded in a suitable opening in 60 the operating shaft 10 to secure the collar 11 to the shaft. This collar is shown as abutting one end of the bearing member 9 to restrict movement of the operating shaft 10 longitudinally of the body portion 5, but 65 permit the same to rotate freely.

One end of the operating shaft 10 is formed with a squared head 13 fitted within a correspondingly-shaped sleeve 14 forming a part of the beveled gear 15, the teeth of 70 which mesh with the teeth 16 of the sleeve 17. The sleeve 17 is mounted for rotation within the head 18, and is formed with a squared opening to accommodate the jaws 19, which may be of various sizes to adapt 75 the tool for use with nuts of various sizes. Thus it will be seen that due to this construction, the jaws 19 may be readily and easily removed and replaced eliminating the necessity of employing securing means for 80 supporting the same.

The head 18 has a circular portion 20 extending at right angles thereto, which circular portion 20 is formed with internal threads to be positioned on the threads 7 of 85 the body portion 5 to secure the head 18 to the body portion.

The outer end of the operating shaft 10 is formed with a squared portion 21 adapted to accommodate the section 22 of the handle, 90 the section 22 being formed with a squared opening to fit over the squared portion 21. A nut 23 is also positioned on one end of the operating shaft 10 to secure the handle thereto.

Formed in the section 22 is an elongated opening 24 adapted to accommodate the bolts 25 that are carried by the section 26 of the operating handle, winged nuts 27 being provided on the bolts 25 to secure the sections 22 and 26 together. From the foregoing it will be seen that the section 26 may be adjusted with respect to the section 22 to lengthen or shorten the operating handle and facilitate the use of the wrench in 105 corners or places where the operating space is restricted.

It might be further stated that the body portion 5, which in operation is gripped by one hand of the operator, is formed with a 110

knurled surface indicated at 28 to insure against the wrench slipping in the hands of the operator.

What is claimed as new is:—

- 5 In a wrench, a tubular body portion having an enlargement at one end thereof, and having external threads, a sleeve positioned within the enlargement, said sleeve having teeth at one end thereof providing a beveled gear, a head having a circular threaded portion adapted to be positioned over the threaded portion of the enlargement to secure the head to the tubular body portion, said head extending laterally from one end 10 of the tubular body portion, a sleeve carry-
- 15

ing a beveled gear cooperating with the first mentioned beveled gear, the last mentioned sleeve being positioned in the head, a shaft operating in the tubular body portion and having a squared end fitted in the first mentioned sleeve, and an adjustable handle at one end of the shaft to rotate the same. 26

In testimony that I claim the foregoing as my own, I have hereto affixed my signature in the presence of two witnesses.

TOMMIE M. RENICK.
